CLAIM

An ornamental design for a grippable bottle, as shown and described.

DESCRIPTION

FIG. 1 is a side elevation view of the grippable bottle of the present invention, the opposite side being a mirror image; FIG. 2 is a front elevation view of the grippable bottle shown in FIG. 1; and,

FIG. 3 is a rear elevation view of the grippable bottle shown in FIG. 1; and, FIG. 4 is top perspective view of the grippable bottle shown in FIG. 1.

The dashed lines are shown in the views for illustrative purposes only and form no part of the claimed design.
